assignors to Gargy Corporation, a corporation of Illinois
Filed Sept. 14, 1962, Ser. No. 223,611
5 Claims. (Cl. 240—147)

This invention relates to a lighting fixture, and is particularly concerned with means for detachably securing a diffuser panel to the fixture.

The lighting fixture comprises a rectangular frame having an outward embossment in each end near one longitudinal side of the frame. The embossments extend upwardly for a purpose hereinafter described. The embossments are longitudinally aligned and are of substantially identical shape except that one of them is short and the other is elongated transversely toward the remote longitudinal edge of the frame. A flat spring positioned in the elongated embossment is secured to the end wall of the frame. The free end of the spring terminates approximately at the end of the transverse elongation in longitudinal alignment with one edge of the short embossment.

The diffuser panel has a pin projecting outwardly from each end near one longitudinal edge thereof. The panel and pin are preferably made of plastic and are integral. The panel is detachably secured to the frame by inserting one of the pins in the short embossment and then turning the panel angularly to position the second pin against the spring in the elongated embossment. The panel is then moved to bring the second pin into axial alignment with the first pin. When the pins are positioned in their respective embossments, and are in axial alignment, the second pin is clear of the free end of the spring. The panel may then be suspended with one longitudinal edge of the frame supported on said pins in pivotal relationship to the adjacent edge of the frame. The free end of the spring, which springs outwardly to its normal position as soon as the second pin is moved out of engagement therewith, is spaced from the wall of the embossment. The spring serves as a stop member and engages the pin if the panel is pushed upwardly while it is in its vertical position. The abutment of the pin against the free end of the spring prevents accidental displacement of the panel from the frame.

Although the fixture is described as having the pins arranged so that the diffuser plate has one longitudinal edge pivoted by the interengagement of the pins and the embossments, it will be understood that the pins may project from the longitudinal edges of the diffuser panel. In such case the diffuser panel would be hinged along one end of the panel.

Each longitudinal edge of the frame is provided with an inwardly extending shoulder adjacent its lower edge, and the diffuser panel is provided with an outwardly extending flange on each longitudinal edge. The longitudinal edge of the diffuser panel adjacent which the pins are located is moved upwardly until each pin abuts the upper edge of the embossment in which the pin is positioned. The opposite longitudinal edge of the diffuser panel is then swung upwardly about the pins as pivots. The upper portion of the embossment is closer to the adjacent edge of the fixture than the lower portion of said embossment. When the pins are in the upper portion of the embossments, the slope of the end wall of each embossment permits the diffuser panel to be shifted laterally over the adjacent shoulder far enough to allow the flange at the longitudinal edge of the diffuser panel remote from the pins to clear the opposite shoulder as the panel is moved pivotally upwardly about the pins. As the last mentioned flange clears the adjacent shoulder, the diffuser panel is shifted laterally in the opposite direction, and is then lowered to rest the flanges at each longitudinal edge of the diffuser panel on

2

the shoulders of the rectangular frame. The spacing of the lower portion of the end wall of the embossment from the adjacent edge of the fixture limits the position of the diffuser panel laterally of the frame when the flanges of the panel rest on the shoulders of the frame. In this position, the panel cannot be shifted laterally far enough to permit the edge of the flange remote from the pins to clear the shoulder on which it normally rests.

In order to obtain access to the interior of the fixture, the longitudinal edge of the panel adjacent the pins is lifted. The end of each of the embossments is sloped to permit the adjacent edge of the panel to be shifted laterally when it is in said raised position. The panel is shifted laterally far enough for the remote flange to clear its shoulder, and the panel is then moved pivotally downwardly about the pins until the panel is suspended in vertical position with each pin engaged with its embossment. If the panel is to be removed from the frame, the end of the panel adjacent the elongated embossment is turned angularly to move its pin toward the free end of the flat spring. The free end of the spring is depressed, either manually or by a suitable tool, and is held down until said pin moves on to the flat surface of the spring. The angular movement is continued, with said pin riding over the spring, until the other pin is moved out of engagement with the short embossment.

The structure by means of which the above mentioned and other advantages of the invention are attained will be fully described in the following specification, taken in conjunction with the accompanying drawings showing a preferred illustrative embodiment of the invention, in which:

FIGURE 1 is a view, partly in elevation and partly in section, showing a diffuser panel mounted in a lighting fixture and showing, in dotted lines, the diffuser panel just before it is moved into the mounted position shown in solid lines;

FIG. 2 is an enlarged fragmentary cross sectional view of the diffuser panel mounted in the frame of a lighting fixture.

FIG. 3 is an enlarged fragmentary exploded perspective view showing one corner of the diffuser panel and the inside corner of the frame in which the panel is to be mounted;

FIG. 4 is an enlarged fragmentary longitudinal sectional view showing one side of the diffuser panel mounted in the frame of the lighting fixture;

FIG. 5 is an enlarged fragmentary horizontal sectional view through the frame of the lighting fixture, showing the diffuser panel in elevation;

FIG. 6 is a fragmentary bottom elevational view showing the diffuser panel mounted in the lighting fixture; and

FIG. 7 is an enlarged fragmentary perspective view of the diffuser panel.

Referring to the drawings, the lighting fixture comprises a rectangular frame 2 and conventional structure for supporting a plurality of fluorescent light tubes 3. Since the present invention is concerned solely with the means for mounting a diffuser panel 4 in a lighting fixture, the structure of the fixture will not be specifically described, except for the rectangular frame. The other portions of the fixture may be of any conventional structure.

The rectangular frame comprises two identical longitudinal side walls 5 and two end walls 7, 8. Side walls 5 and 6 have inwardly extending shoulders 9 and 10, respectively. The shoulders are parallel and are horizontal when the fixture is in its normal horizontal position. The end wall 8 is provided with an outward embossment 11 adjacent longitudinal edge 5 and end wall 9 is provided with an outward embossment 12, also adjacent longitudinal edge 5.

As shown best in FIGS. 2 and 3, the embossment 11 is formed to provide a substantially horizontal bottom wall 13, an end wall 14 that extends upwardly and outwardly toward longitudinal side wall 5, and a top wall 15 that slopes downwardly and inwardly to the region indicated at 16 in FIG. 2. The description of embossment 11 up to this point applies also to embossment 12. The only difference between the embossments is that the inner edge of embossment 12 terminates in the region 16 and top wall 15 extends downwardly to meet bottom wall 13 to form a closed figure. Embossment 11, however, is elongated in the transverse direction. Inwardly of the region 16 walls 17 and 13 extend parallel to each other for a substantial distance.

A flat spring 18 is riveted inside the embossment 11, as indicated at 19, with its free end terminating adjacent the region 16. The spring is flexed so that when its free end is not restrained it is spaced outwardly from the wall of the embossment to which it is riveted.

The diffuser panel 4 comprises a rectangular bottom 20 having upstanding longitudinal side walls 21, 22 and upstanding end walls 23, 24. Side walls 21 and 22 are provided with horizontal outwardly extending flanges 25 and 26, respectively. The overall width of the diffuser panel 4 is greater than the distance between the inner edges of shoulders 9 and 10, but the width of the diffuser panel exclusive of flanges 25 and 26 is less than said distance. End wall 23 has a pin 27 extending outwardly therefrom adjacent side wall 21, and end wall 24 has a pin 28 extending outwardly therefrom in axial alignment with pin 27. Although the diffuser panel is preferably an integral structure molded of suitable plastic, it will be understood that it may be of any suitable material and may be fabricated of a plurality of components.

When the diffuser panel 4 is to be mounted in the frame 2, the panel is moved to insert the pin 28 into the short embossment 12 and the panel is then turned angularly to position the pin 27 into the elongated portion of embossment 11. The turning movement of panel 4 is continued to slide pin 27 over the spring 18. As the pin 27 moves over the spring it presses the spring flat against the wall of the embossment. As soon as the pin 27 passes the free end of the spring, the spring snaps back to its normal position, in which it is spaced from the wall of the embossment 11. The panel may be suspended by the engagement of pins 27 and 28 with the embossments 11 and 12, respectively, with side wall 22 hanging down freely. In this position the interior of the fixture is accessible for replacement of fluorescent light tubes 3.

The side of panel 4 adjacent the pins 27 and 28 is then moved upwardly until each of said pins abuts the upper edge of its embossment. The outward slope of end walls 14 of the abutments permits the panel to be shifted laterally outwardly as the pins move upwardly in the embossments. This lateral shift is sufficient to cause the flange 26 to clear the shoulder 10 as the diffuser panel is swung pivotally upwardly about the pins 27 and 28. The panel is lowered horizontally when the flange 26 is above the shoulder 10, and the panel is shifted laterally in the opposite direction by the slope of end wall 14 so that flange 25 is seated on shoulder 9 and flange 26 is seated on shoulder 10. The diffuser panel is released by a reversal of the steps described above.

When the diffuser panel is suspended from one side, the spring 18 prevents accidental turning movement of the panel to an extent sufficient to displace the pin 27 from the elongated embossment 11. The resilience of the spring spaces its free end from the wall of the embossment so that if the panel is turned the pin 27 will abut the spring which then acts as a stop member. If the panel is to be removed from the frame, the free end of the spring is pressed against the wall of the embossment, either manually or by any suitable tool, until the panel is turned far enough for the pin 27 to ride over the free end of the spring.

Although we have described a preferred embodiment of the invention in considerable detail, it will be understood that the description thereof is intended to be illustrative, rather than restrictive, as many details of construction may be modified or changed without departing from the spirit or scope of the invention. Accordingly, we do not desire to be restricted to the exact structure described.

We claim:

1. A lighting fixture comprising a rectangular frame having an open bottom and a diffuser panel mounted in said frame, said frame comprising two longitudinal walls each provided with an internal shoulder and two end walls each provided with an outward embossment adjacent one of said longitudinal walls, said diffuser panel having two longitudinal side walls and two ends, at lateral flange extending outwardly from each side wall of said diffuser panel, the total width of said diffuser panel and both of said flanges being greater than the internal distance between the shoulders of said frame, the width of said diffuser panel exclusive of said flanges being less than the internal distance between the shoulders of said frame, said diffuser panel being adapted to fit within the open bottom of said frame with said flanges seated on said shoulders, and a pin extending longitudinally from each end of said diffuser panel, said pins being axially aligned, one of said embossments having an elongation extending toward the remote longitudinal edge of said frame, said elongation permitting one of said pins to be moved transversely of said frame into engagement with said one embossment when said other pin is positioned in said other embossment, said embossments each having an upper portion extended toward the adjacent edge of said frame, the upper portions of said embossments permitting said diffuser panel to be shifted laterally of said frame above the level at which said diffuser panel is normally seated in said frame.
2. A lighting fixture comprising a rectangular frame having an open bottom and a diffuser panel mounted in said frame, said frame comprising two longitudinal walls each provided with an internal shoulder and two end walls each provided with an outward embossment adjacent one of said longitudinal walls, said diffuser panel having two longitudinal side walls and two ends, a lateral flange extending outwardly from each side wall of said diffuser panel, the total width of said diffuser panel and both of said flanges being greater than the internal distance between the shoulders of said frame, the width of said diffuser panel exclusive of said flanges being less than the internal distance between the shoulders of said frame, said diffuser panel being adapted to fit within the open bottom of said frame with said flanges seated on said shoulders, a pin extending longitudinally from each end of said diffuser panel, said pins being axially aligned, one of said embossments elongation extending toward the remote longitudinal edge of said frame, said elongation permitting one of said pins to be moved transversely of said frame into engagement with said one embossment when said other pin is positioned in said other embossment, and means positioned in said elongation and engageable with the pin in the embossment adjacent said elongation preventing accidental displacement of either pin from its embossment, said embossments each having an upper portion extended toward the adjacent edge of said frame, the upper portions of said embossments permitting said diffuser panel to be shifted laterally of said frame above the level at which said diffuser panel is normally seated in said frame.
3. A lighting fixture comprising a rectangular frame having an open bottom and a diffuser panel mounted in said frame, said frame comprising two longitudinal walls each provided with an internal shoulder and two end walls each provided with an outward embossment adjacent one of said longitudinal walls, said diffuser panel having two longitudinal side walls and two ends, a lateral flange ex-

tending outwardly from each side wall of said diffuser panel the total width of said diffuser panel and both of said flanges being greater than the internal distance between the shoulders of said frame, the width of said diffuser panel exclusive of said flanges being less than the internal distance between the shoulders of said frame, said diffuser panel being adapted to fit within the open bottom of said frame with said flanges seated on said shoulders, a pin extending longitudinally from each end of said diffuser panel, said pins being axially aligned, one of said embossments having an elongation extending toward the remote longitudinal edge of said frame, said elongation permitting one of said pins to be moved transversely of said frame into engagement with said one embossment when said other pin is positioned in said other embossment, and resilient means secured in said elongation to prevent accidental displacement of said one pin from said one embossment, said means being so shaped as to permit movement of said one pin from said elongation into said one embossment and to normally prevent movement of said one pin from said one embossment into said elongation, said embossments each having an upper portion extended toward the adjacent edge of said frame, the upper portions of said embossments permitting said diffuser panel to be shifted laterally of said frame above the level at which said diffuser panel is normally seated in said frame.

4. A lighting fixture comprising a rectangular frame having an open bottom and a diffuser panel mounted in said frame, said frame comprising two longitudinal walls each provided with an internal shoulder and two end walls each provided with an outward embossment adjacent one of said longitudinal walls, said diffuser panel having two longitudinal side walls and two ends, a lateral flange extending outwardly from each side wall of said diffuser panel, the total width of said diffuser panel and both of said flanges being greater than the internal distance between the shoulders of said frame, the width of said diffuser panel exclusive of said flanges being less than the internal distance between the shoulders of said frame, said diffuser panel being adapted to fit within the open bottom of said frame with said flanges seated on said shoulders, a pin extending longitudinally from each end of said diffuser panel, said pins being axially aligned, and means whereby each of said pins may be engaged with one of said embossments, said embossments each having its end closest to the adjacent edge of said frame inclined toward said adjacent edge in an upward direction, the shape of said

embossments permitting said diffuser panel to be shifted laterally toward said adjacent edge as it is moved upwardly from its position on said shoulders and causing it to be automatically shifted laterally in the opposite direction to seat said flanges on said shoulders when said panel is lowered in horizontal position with its pins positioned in said embossments.

5. A lighting fixture comprising a rectangular frame and a diffuser panel mounted in said frame, said frame having two longitudinal walls, two end walls and an open bottom, each of said end walls having an outward embossment adjacent one of said longitudinal walls, said diffuser panel having a pin extending longitudinally from each end, said pins being axially aligned, the longitudinal distance between the outer ends of said pins being greater than the internal length of said frame, one of said embossments having an elongation extending transversely of said frame toward the remote longitudinal edge of said frame, said elongation permitting one of said pins to be engaged therewith when said other pin is engaged with said other embossment, said one pin being movable in said elongation by a turning movement of said panel until it is engaged with said one embossment, the total width of said diffuser panel being less than the width of said open bottom, means projecting inwardly from the longitudinal walls of said frame to support said panel in horizontal position within said open bottom, the upper portion of said embossments being extended toward said adjacent longitudinal edge to provide clearance for lateral movement of said diffuser panel beyond the position occupied by said panel during normal use of said fixture by a distance at least equal to the overlap between said means and the longitudinal wall remote from said embossments, whereby said panel may be shifted laterally with said pins in said embossments to position both longitudinal walls within said rectangular frame above said means, and then moved downwardly to rest on said means.
